UNITED STATES PATENT OFFICE.

FRANK O. HOAGLAND, OF BRIDGEPORT, CONNECTICUT, ASSIGNOR, BY MESNE ASSIGNMENTS, TO PRATT & WHITNEY COMPANY, OF NEW YORK, N. Y., A CORPORATION OF NEW JERSEY.

INTERNAL-GRINDING MACHINE.

Application filed February 28, 1923, Serial No. 621,785. Renewed May 12, 1926.

This invention relates to a machine for grinding the interiors of cylinders and other hollow bodies and preferably is constructed in a form similar to that of the ordinary 5 types of upright drill.

The principal objects of the invention are to provide a machine of this character, in which the work is supported on a table having a planetary or orbital motion and 10 which preferably does not move vertically. The grinding wheel in the embodiment of the invention illustrated is advanced in a downward direction toward the work, with means provided for rotating the grinding 15 wheel on its own axis. Means also are provided for actuating the work in a planetary path on a parallel axis combined with a parallel motion arrangement for insuring the movement of the work in a uniform manner 20 without side motion.

Another object of the invention is to provide a machine of this type with means for adjusting the radius at which the work is actuated and for adjusting it to as fine a 25 degree as may be desired; also another object is to provide for securing this adjustment by a straight line motion of an eccentric pin for driving the work; and finally it is another object to provide a convenient form of 30 gearing for securing adjustments in the radius of movement of the work, operable when the work is rotating.

The invention also involves improvements in the details of construction and combinations of parts for accomplishing these 35 results.

Reference is to be had to the accompanying drawings in which

Fig. 1 is a side elevation of an internal 40 grinding machine constructed in accordance with this invention;

Fig. 2 is a front view of a portion of the same.

Fig. 3 is a central sectional view of the 45 base and work table, and the mechanism therein on an enlarged scale.

Fig. 4 is a similar view on a still further enlarged scale of the lower portion thereof.

Fig. 5 is a horizontal sectional view on the 50 line 5—5 of Fig. 4.

Fig. 6 is a plan of the work table showing the parallel motion connections partly in dotted lines and partly broken away to show them in detail.

Fig. 7 is a plan of the center pin adjusting mechanism.

Fig. 8 is a sectional view of the same on the line 8—8 of Fig. 3; and

Figs. 9, 10, and 11 are sectional views of the parallel motion connections on the lines 60 9—9, 10—10 and 11—11 respectively of Fig. 6.

I have shown the invention as applied to a machine frame 10 patterned largely after the ordinary upright drill. This frame has 65 a base 11 for supporting the frame 10 and the latter extends upwardly to a convenient height, and I have shown it as provided with pulleys 12 and power transmission mechanism 13 for rotating a drill spindle 14. This 70 drill spindle is mounted in a quill 15, having a rack 16 as is well understood in this art, adapted to be raised and lowered by a pinion, not shown, connected with a pair of handles 17 adapted to be turned by the 75 operator for the purpose of raising and lowering this drill spindle. This invention is not limited to its use in connection with a drill or drill spindle or any equivalent thereof, but can conveniently be used in connection with such a device used for drilling, 80 tapping, reaming or the like.

This quill 15 is supported in a head 18 which extends backwardly towards the frame and is provided with dove tail construction adapted to be moved up and down the frame 10 in vertical ways 19. This is done by a rack and pinion construction operated by a hand wheel 20 in a well known manner or by any equivalent means. The 90 parts so far described are well known and do not constitute part of this invention except in combination with the parts now to be described.

In this vertical adjustable head 18 is located a sleeve 21. In this is located a spindle 22 connected, to be driven either from the shaft on which the pulley 12 is located, or in any other desired way. It is arranged to be driven independently of the spindle 100 14, and in fact the drill spindle and its connected parts can be omitted entirely within the scope of this invention.

I have shown at the bottom of the frame a main driving shaft 25 having tight and loose pulleys 26 thereon, through which it is driven. This shaft is shown as provided with a cone pulley 27 for driving the cone 105

pulley 12. This shaft 25 drives a shaft 25^a on which is a worm 28 meshing with and driving a worm wheel 29 keyed to a vertical hollow shaft 30 located in a stationary hollow base 31 which extends upwardly and forms a support for a horizontal table 32 for supporting the work. The rotation of this hollow shaft 30 is of course communicated directly to a head 33 located thereon in the upper part of the base under the table. Extending through the hollow shaft is a central shaft 35 which is centered therein and is provided with two opposite bevel gears 36 and 37 of the same size and number of teeth. The gear 36 is keyed to the shaft 35 and the gear 37 is free with respect thereto and constitutes an independently rotatable member. It is mounted on a sleeve 38 on the bottom of the shaft and has a bearing in a stationary bevel gear 39 below it. This stationary gear 39 is fixed by screws 46 or the like on a cup-shaped support 40 in the base of the machine.

Free on the shaft 35 between the beveled gears 36 and 37 is a hub 41 within which, therefore, this shaft may rotate and which also rotates itself. This constitutes a support for two diametrically opposite studs 42 which therefore act together and virtually constitute a transverse shaft which does not rotate on its own axis, but does rotate as a whole on a vertical axis. These two studs carry two bevel gears 43 and 44. The gear 44 meshes with the two gears 36 and 37, while the gear 43 meshes with the gear 39, and with a bevel gear 45 which is keyed to the hollow shaft 30. I have shown the two gears 39 and 45 as of the same diameter and number of teeth, and the two gears 36 and 37 also as of the same diameter and number of teeth.

Now let it be assumed that the gear 37 is held in stationary position. It has been stated that the gear 39 is absolutely fixed in stationary position. Now the rotation of the hollow shaft 30 carries with it the gear 45 and as the gear 39 is stationary causes the gear 43 to roll around on the gear 39. This rotates the shaft 42 with the shaft 30 at half speed and it takes with it the bevel gear 44 and rolls that around the stationary gear 37 at the same speed as the gear 43, and that necessarily, on account of the operations above mentioned, rotates the gear 36 at exactly the same speed as the gear 45. Therefore, under the conditions mentioned, that is, with the gear 37 held stationary the two shafts 30 and 35 will rotate exactly in unison.

It may be stated at this point that the shank of the gear 37 has keyed to it a bevel or other gear 48, and that meshing with this is a gear 49 on an inclined upwardly extending shaft 50. This shaft can be turned through a pair of bevel gears 51 by a shaft

52 mounted in a suitable bearing on the frame 31, and having a handle 53. This shaft 52 has a graduated bevel scale 54 fixed to it to turn with it, and the bearing 55 on which this shaft is supported has a registering conical surface 56 having a zero point on it for indicating the amount which this shaft 52 is turned. Indirectly it indicates the eccentricity of the center of the table 32 and therefore the radius of motion of the table as will appear.

It will be seen that this handle 53 can be turned either forward or backward and thus turn the gear 37 and, for the time being, change the relative speed of the two shafts 30 and 35 so that one of them will rotate a little faster than the other.

On the top of the interior shaft 35 is a bevel gear 55^a meshing with a gear 56^a on horizontal shaft 57 supported in a suitable bearing on the rotating head 33. This shaft is screw threaded and is provided with a threaded nut 57^a which can be moved along the shaft by turning it. Extending from this nut there is a pin 58 projecting into a slide 59 above, and there is also a screw 60 extending down into the nut from the slide 59 so that the two work together and always move together. This slide is mounted to move in a radial direction on ways 61 carried by the rotary head 33. This slide 59 has a depression or socket in which there is an anti-friction bearing 62 which carries within it the end of a stud 63 constituting a center pin and projecting down from an opening through the table 32 in which opening this pin accurately fits. The top of the opening is enlarged for receiving the head 64 of the pin which is held in position by screws, so that the top of the table is flat and continuous. It will be understood of course that it is provided with T-slots 65 whereby the piece of work as W can be secured to the table by the usual headed bolts and nuts.

From what has been said, it will be apparent that when the scale 54 is turned to the desired point and the gear 37 is held in stationary position, the rotation of the hollow shaft 30 will cause the inner shaft 35 to rotate with it at exactly the same speed. Therefore there will be no relative rotation between the gears 55^a and 56^a. Also no motion of the slide 59 will occur, but the pin 63, having previously been set to some eccentric position, will rotate about the center of the shaft 35 and cause a motion of the table 32 with it in its plane. Now when it is desired to feed the work one way or the other to increase the cut or release it from the cutter, the handle 53 is turned in one direction or the other. This obviously causes relative rotation of the gears 55^a and 56^a, due to the fact that the two shafts 30 and 35 will then rotate at different speeds while the shaft 52

is being turned. In this way the eccentricity of the pin 63 is adjusted to the finest degree desired, reference being had to the scale 54, and the radius of motion of the table is 5 varied accordingly.

The motion of the table 32 that has been described above, without other control, would be a floating rotation, and it would be capable of angular or swinging motion constituting a creeping about the eccentric pin 63. In order to keep the table always in parallel positions, that is, with any line thereon always pointing in the same direction irrespective of rotation and adjustments,

15 I provide a parallel motion as follows:—

On the top of the base 31 are two vertical studs 70. Pivotedally mounted on these studs 70 are two links 71 of exactly the same effective length; and also pivotedally mounted 20 on the bottom of the table are two corresponding vertical studs 72 and pivoted on them are two links 73 of the same effective lengths as the links 71. The two links 71 and 73 of each pair are connected to each 25 other by a stud 74. Therefore there are two of these studs 74 both in vertical position supported solely by the links and these two studs are connected by a longitudinal link 75.

As the two studs 70 are stationary and 30 at a constant distance apart and as the two studs 72 are movable with the table but always at the same constant distance apart, the link motion above described constitutes a parallel motion; therefore the table will be 35 constrained to move in a parallel manner; that is, any line drawn on the table can not at any time under any conditions, when the parts are in proper place, be made to change its direction. This insures accurate grinding 40 as it prevents circumferential creeping of the table.

In operation the grinding wheel spindle 22 is set in rotation, and this spindle may be considered as centrally located. The table 45 32 is then set in motion by the driving mechanism above described. If the pin 63 is in exactly central position at this time the table will have no motion, but as soon as the handle 53 is turned in either direction 50 the stud 63 will be moved thereby out of its central position, and the table will be actuated about the axis of the shaft 35 with an amplitude of radius that is given it by the eccentricity of the pin 63. The work W is 55 required to be accurately located relative to the wheel on spindle 22. This may be manually accomplished by means of the T slots 65 in the table 32. As soon as the wheel begins to cut, the handle 53 is left in a stationary position while the grinding wheel is traversed along the work as far as it is to be ground. When the reduction has taken place 60 throughout the length of the work, the handle 53 can be turned as little as may be 65 desired to add to the depth of the cut and

this can be controlled within very fine limits. The traverse of the wheel is done in the present instance by the operation of the hand wheel 20 and is within the control of the operator.

From this it will be seen that the adjustment of the grinding wheel toward and from the work is controlled very finely by the operator and that the work has a true planetary or orbital motion which cannot be disturbed in any way in this machine. Also the fineness of adjustment is within the control of the operator at all times, and the same instrumentality that controls that also controls the movement of the work out of the path of the grinding wheel so that the latter can be raised up out of the work.

Although I have described this as performing the operation of internal grinding in an engine cylinder or the like, I am 85 aware of the fact that it is suitable for many other kinds of internal grinding and also for external grinding. Although I have illustrated and described only a single form of the invention, I am aware of the fact that 90 modifications can be made therein by any person skilled in the art, without departing from the scope of the invention as expressed in the claims, and that the invention can be used independently of the drill features here- 95 in referred to.

Having thus described my invention what I claim is:—

1. In a grinding machine, the combination 100 with a rotary grinding wheel spindle adapted to be adjusted in an axial direction, of a work supporting table capable of movement about an axis parallel to the axis of the spindle and having means for clamping the work thereon, a rotary shaft, a slide mounted thereon to move radially and adapted to engage the table to move the table with it, whereby the table can be actuated by the rotation of said shaft, and means for adjusting the position of said slide radially while 110 the shaft and table are moving.

2. In a grinding machine, the combination 115 with a rotary grinding wheel spindle adapted to be adjusted in an axial direction, of a work supporting table located beyond the end of said spindle, said table being capable of movement about an axis parallel with the axis of the spindle and having means for clamping the work thereon, a rotary shaft extending toward the said table, 120 a rotary head surrounding the shaft, a slide mounted to move radially on said head, a pin mounted on said slide and adapted to engage the table to move the table with it, whereby the table can be actuated by the 125 rotation of said shaft when the pin is in an eccentric position thereon, and means for adjusting the position of said slide radially while the shaft and table are moving.

3. In a grinding machine, the combina- 130

- tion with a vertically adjustable and rotatable grinding wheel spindle, of a work table mounted below said spindle, means for clamping the work on the top of said table, 5 a pin connected with the center of said table, a rotary head below the table on which said pin is supported, said head having ways thereon, a slide on said ways arranged to move radially, a bearing on said slide in which said pin is mounted, and means capable of being operated when the head is rotating for adjusting said slide radially, and therefore adjusting the eccentricity of said pin.
- 15 4. In a grinding machine, the combination with a rotary grinding wheel spindle adapted to be adjusted, of a work supporting table capable of movement on an axis parallel to the axis of the spindle, and having 20 means for clamping the work thereon, a rotary shaft, a pin mounted to move radially and to rotate and adapted to engage the table to move the table with it, a hollow shaft on which said pin is movably mounted and through which the first named shaft passes, means for rotating the hollow shaft, and means connected with the hollow shaft for normally rotating the inner shaft at the same speed.
- 25 5. In a grinding machine, the combination with a rotary grinding wheel spindle, of a rotary work supporting table having means for clamping the work thereon, a rotary shaft, a hollow head rotatable about the shaft, a slide mounted to move radially in said head, a pin mounted on said slide and adapted to engage the table to move the table with it, whereby the table can be actuated by the rotation of said head when the 30 pin is in an eccentric position thereon, and means for adjusting the eccentricity of said pin while the shaft and head are rotating, said means comprising a hollow shaft on which said head is mounted and through which the first named shaft passes, means for positively rotating the hollow shaft, a rotary member, and connections with the rotary member for rotating the inner shaft from the hollow shaft at exactly the same speed when the rotary member is held in stationary position and for causing them to rotate at unequal speeds whenever the said rotary member is in motion.
- 35 6. In a grinding machine, the combination with a rotary grinding wheel spindle, of a work supporting table, a rotary shaft, a rotary head surrounding the shaft, a slide mounted to move radially in said head, a pin mounted on said slide and adapted to engage the table to move the table with it, whereby the table can be actuated by the rotation of said head when the pin is in an eccentric position thereon, a second shaft on which said head is mounted, means for rotating the second shaft, a gear fixed on the 40 second shaft, a stationary gear of the same size and number of teeth, a transverse shaft on the second shaft, a third gear thereon meshing with both of said gears, a freely rotatable gear, a gear fixed on the first shaft, 70 and a gear meshing with the last two named gears and located on the transverse shaft, whereby when the freely rotatable gear is held fixed the first shaft will be rotated at the same speed as the second shaft by said system of gears.
- 45 7. In a grinding machine, the combination with a rotary grinding wheel spindle, of a work supporting table, a rotary shaft, a rotary head surrounding the shaft, a pin mounted in said head and adapted to engage the table to move the table with it, whereby the table can be actuated by the rotation of said head when the pin is in an eccentric position on the head, a hollow shaft on 80 which said head is mounted and through which the first named shaft passes, means for rotating the hollow shaft, a bevel gear fixed on the hollow shaft, a stationary bevel gear of the same size and number of teeth, 85 a transverse shaft, a third bevel gear thereon meshing with both of said bevel gears, a freely rotatable bevel gear, a bevel gear of the same size and number of teeth as the freely rotatable bevel gear fixed on the inner shaft, a bevel gear meshing with the last two named bevel gears and located on the transverse shaft, whereby when the freely rotatable bevel gear is held fixed the inner shaft will be rotated at the same 90 speed as the hollow shaft by said system of bevel gears, and adjustable means for turning the freely rotatable gear for the purpose of changing the eccentricity of said pin and the radius about which the table is actuated.
- 50 8. In a grinding machine, the combination with a rotary grinding wheel spindle, of a work supporting table, a rotary shaft extending toward said table, a rotary head surrounding the shaft, a slide mounted to move radially in said head, a pin mounted on said slide and adapted to engage the table to move the table with it, whereby the table can be actuated by the rotation of said head when the pin is in an eccentric position thereon, a hollow shaft on which said head is mounted and through which the first 100 named shaft passes, means for rotating the hollow shaft, and means connected with the hollow shaft for normally rotating the inner shaft at the same speed as said hollow shaft, said means comprising a rotary member and connections with the rotary member for rotating the inner shaft with the hollow shaft at exactly the same speed when the rotary member is held in stationary position and for causing them to rotate at unequal speeds whenever the said rotary member is in motion, gear teeth on said rotary member,
- 55 105 110 115 120 125 130

- a shaft having a gear meshing with said gear teeth, a handle for turning said shaft, and means on said handle for indicating the amount which the shaft is turned.
5. 9. In a grinding machine, the combination with a rotary grinding wheel spindle, of a work supporting table, a rotary shaft, a rotary head surrounding the shaft, a slide mounted to move radially in said head, a pin mounted on said slide and adapted to engage the table to move the table with it, whereby the table can be actuated by the rotation of said head when the pin is in an eccentric position thereon, means for adjusting the eccentricity of said pin while the shaft and head are rotating, and a parallel motion device connecting the table with a stationary part of the frame for insuring the actuation of the table in such a manner that any line thereon maintains the same angular position during the movement of the table.
10. 10. In a grinding machine, the combination with a rotary grinding wheel spindle and means for feeding it, of a base, a work table movably mounted on said base and having means for clamping the work thereon, a head rotatable beyond the table, a slide mounted on said head, a pin carried by the slide and engaging the table for moving the table with the pin, means for adjusting the position of the pin, whereby when it is in eccentric position the rotation of the head will cause the table to be actuated, a pair of parallel links pivoted to said base, another pair of parallel links pivoted to the first named links and also pivoted to the table, said links all being of the same length, and a connecting link connected at its opposite ends with the links of the two pairs at the point at which they are pivoted together for insuring a parallel motion of the table.
15. 11. In a grinding machine, the combination with a rotary grinding wheel spindle and means for feeding it, of a base, a work table movably mounted on said base, a pin engaging the table for moving the table with the pin, means for rotating the pin, means for adjusting the position of the pin, whereby when it is in eccentric position the rotation will cause the table to be actuated, a pair of parallel links pivoted to said base, another pair of parallel links pivoted to the first named links and also pivoted to the table, said links all being of the same length, and a connecting link connected at opposite ends with the links of the two pairs at the point at which they are pivoted together for insuring a parallel motion of the table.
20. 12. In a grinding machine, the combination with a rotary grinding wheel spindle, of a base, a work table movably mounted on said base and having means for clamping the work thereon, a pair of parallel links
- pivoted to said base, another pair of parallel links pivoted to the first named links and also pivoted to the table, said links all being of the same length, and a connecting link connected at opposite ends with the links of the two pairs at the point at which they are pivoted together for insuring a parallel motion of the table.
25. 13. A work supporting and actuating table for internal cylindrical grinding machines comprising in combination, a base, a table movable thereon, an eccentric rotatably mounted in said base and engaging said table, and a parallel motion linkage adapted to maintain the table in parallel positions while it is being actuated in a planetary path.
30. 14. A work supporting and actuating table for internal cylindrical grinding machines comprising in combination, a base, a table movable thereon, an eccentric rotatably mounted in said base and engaging a circular opening in said table, means to adjust the eccentricity of said eccentric, and a parallel motion linkage adapted to maintain the table in parallel positions while it is being actuated in a planetary path.
35. 15. A work supporting and actuating table for internal cylindrical grinding machines comprising in combination, a base, a table movable thereon, an eccentric rotatably mounted in said base and engaging a circular opening in said table, means to adjust the eccentricity of said eccentric during actuation of said table, and a parallel motion linkage adapted to maintain the table in parallel positions while it is being actuated in a planetary path.
40. 16. A work supporting and actuating table for internal cylindrical grinding machines comprising in combination, a base, a table movable thereon, an eccentric rotatably mounted in said base and engaging a circular opening in said table, and a parallel motion linkage comprising a plurality of pairs of parallel links pivotally engaging said base and table adapted to maintain the table in parallel positions while it is being actuated in a planetary path.
45. 17. The combination in a machine having a work supporting platen adapted for motion in a horizontal plane, of single means to rotate the platen in said plane, an intermediate member movable bodily in an arcuate path, and means including parallel links pivotally connected at one end to the ends of the platen and at their opposite ends to the intermediate member to maintain said platen parallel to a given line in said plane.
50. 18. The combination in a machine having a work supporting platen adapted for motion in a horizontal plane, of a single eccentric adapted to drive the platen, and means to maintain the platen parallel to a given line in said plane including a floating inter-

mediate member movable bodily in an arcuate path, parallel links pivotally connecting said member and the platen, and parallel links connecting said member and a fixed support.

19. The combination in a machine having a work supporting platen adapted for motion in a horizontal plane, of means to move one point of the platen in a circular path in said plane, and means to maintain the platen parallel to a given line in said plane, said means including a floating member and two pairs of parallel links, said pairs being pivotally connected respectively to said member and a fixed support and to the platen and member, one end of each link of a pair being attached to spaced points of the floating member.

20. The combination in a machine having a work supporting platen adapted for motion in a horizontal plane, of means to move one point of the platen in circular paths in said plane of varying diameters, and means to maintain the platen parallel to a given line in said plane, said means including a floating member having points restrained to arcuate motion in said plane, and parallel links pivotally connected to said member and to the platen.

21. The combination in a grinding machine of a platen slidably mounted in a horizontal plane for movement in any direction, means maintaining said platen parallel to a given line in said plane comprising

ing an intermediate member and two pairs of parallel links connecting said intermediate member to a fixed support and to said platen, one end of each link of a pair being attached to spaced points of the floating member, and means for driving the platen, said driving means comprising a single vertically-disposed eccentric mounted beneath said platen.

22. The combination in a grinding machine having a work supporting platen mounted for motion on a fixed table, of adjustable eccentric means for driving a point in said platen in a circular path, a floating member, parallel links pivotally connected at their ends to said member and to the table, and parallel links pivotally connected at their ends to said member and to the platen.

23. The combination in a grinding machine having a platen slidably mounted on a table, of means for controlling the motion bodily of said platen in circular paths of varying diameters comprising a pair of parallel links pivotally connected at one end to the table, a pair of parallel links pivotally connected at one end to the platen, and a floating member pivotally connected at separate points to the opposite ends of each of said pairs of links.

In testimony whereof I have hereunto affixed my signature.

FRANK O. HOAGLAND.
